UNITED STATES PATENT OFFICE.

LEON DION, OF NATICK, ASSIGNOR TO GEORGE S. TROWBRIDGE, TRUSTEE,
OF NEWTON, MASSACHUSETTS.

KEY-FASTENER.

SPECIFICATION forming part of Letters Patent No. 268,640, dated December 5, 1882.

Application filed August 7, 1882. (No model.)

To all whom it may concern:

Be it known that I, LEON DION, of Natick, county of Middlesex, State of Massachusetts, have invented an Improvement in Fastening 5 Devices for Door-Keys, of which the following description, in connection with the accompanying drawings, is a specification.

My invention relates to a fastening device for keys of door-locks, to prevent the said 10 keys from being turned by means of nippers from the outside of the door, or from being removed from the lock so as to permit the insertion of a false key.

It consists in the combination, with a key 15 having a flat or squared shank, of a fastening device consisting of a fork provided with a projection and arranged to slide across the key-hole in a guide made in the usual escutcheon, the fork embracing and holding the 20 shank of the key after it has been turned to throw the bolt, the projection of the fork engaging a notch in the escutcheon and being thereby held in place. The said fork is arranged, as shown, relative to the key-hole to 25 engage the shank of the key after it has been turned to throw the bolt and while its bit rests against the inside of the lock-plate, so that it cannot be withdrawn until brought in line with the key-hole, a movement which is 30 prevented by the fastening device. A spring co-operating with the fork holds it so that the fork cannot be disengaged by an instrument inserted through the key-hole from the outside of the door.

Figure 1 shows in side view a portion of a 35 door having a lock and escutcheon provided with a key held by a fastening device in accordance with this invention; Fig. 2, a perspective view of the key-fastening device detached; and Fig. 3, a section on the line x , x , Fig. 1.

The lock, of which only the bolt a appears, 40 may be of any usual construction, it being operated by a key, b , having in this instance a flat shank made from sheet metal. The key is surrounded with an escutcheon or key-hole plate, c , provided with a guide, d , for the key-fastening device or fork e . This key-fastening device is shown as a metal bar, forked or slot-

ted at 2 to embrace the shank of the key b 50 and prevent it from being rotated, the said device sliding across the round portion 3 of the key-hole at such an angle as to engage the key after it has been completely turned to throw the bolt and while its bit is in engagement with the inner face of the lock-plate. 55

The fastening device e has on its upper face a locking-projection, 4, that engages a notch in the escutcheon when the said device is pushed in to embrace the key-shank, the said 60 fastening device e being pressed outward from the door by the spring n to throw the said projection 4 into its notch, and it will be seen that an instrument inserted through the key-hole to slide back the device e would tend to 65 hold the said locking-projection more closely in its notch. When desired to unfasten the key the fastening device is pressed back by means of the projecting portion 5, which serves as a handle to disengage the projection 4, and 70 is then withdrawn from its position across the key-hole.

The fastening device e is provided with stop-projections 6 at its under side, which engage the end of a groove, 7, therefor in the 75 wood-work, (see Fig. 3,) to prevent it from being wholly withdrawn from the escutcheon.

It will be seen that by this arrangement the key is fastened when its bit is engaged with the inner portions of the lock and out of line 80 with the slotted portion 8 of the key-hole, Fig. 1, so that it cannot be forced longitudinally from the lock. In this my invention the escutcheon overlies the key-fastener, and guides and holds it in place, forming a very 85 compact, strong, and cheap arrangement of parts, and the fastener e , when it engages the key, is almost concealed from sight.

I claim—

1. The escutcheon c , provided at its under 90 side with a guide-groove and notched at its edge, and the fastening-fork adapted to slide across the key-hole of the escutcheon and engage the flattened portion of the key, and also provided with a locking-projection, 4, combined with a spring to cause the fastening-fork to engage the notch in the escutcheon, substantially as described. 95

2. The escutcheon *c*, provided with the guide-groove and notch, combined with the sliding notched or forked key-fastening device provided with a locking-projection, *4*, and stop-projections *6*, and with the spring, whereby the said locking-projection is thrown into engagement with the notch, the stop-projection preventing the withdrawal of the key-fastening device, all as described.

In testimony whereof I have signed my name to this specification in the presence of two subscribing witnesses.

LÉON DION.
